CLAIM

The ornamental design for a television receiver as shown and described.

DESCRIPTION

FIG. 1 is a front, right, top perspective view of a television receiver showing our new design in a first state in which a light shielding layer is not spread;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front, right, top perspective view thereof in a second state in which the light shielding layer spreads completely in the left-right direction;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is an enlarged view of portion "15" of FIG. 1;

FIG. 16 is an enlarged view of portion "16" of FIG. 5; and, FIG. 17 is an enlarged view of portion "17" of FIG. 7.

The broken lines depict portions of the television receiver that form no part of the claimed design. The dot-dot-dash broken lines in FIGS. 1, 5, 7 and 15-17 are included to show the boundaries of the enlarged views and form no part of the claimed design.
